Wilmington, Del., a corporation of Delaware

Application April 15, 1938, Serial No. 76,533

Term of patent 14 years

To all whom it may concern:

Be it known that I, Raymond Guerlain, a citizen of the Republic of France, residing at Paris, France, have invented a new, original, and ornamental Design for a Box, of which the following is a specification, reference being had to the accompanying drawing, forming part thereof.

In the drawing:

Fig. 1 is a perspective view of a box showing my new design;

Fig. 2 is an end view.

The salient feature of this design is the ornamentation of the cover consisting of a series of oblique bars or ribs intersecting each other to form a series of quadri-lateral figures of equal size, said bars or ribs being lightly raised or embossed upon the top of the cover.

I claim:

The ornamental design for a box, as shown and described.

RAYMOND GUERLAIN,
